[57] ABSTRACT

A two-stage blower is driven by a liquid-cooled engine. The first stage of the blower operates in a chamber divided from an intake plenum for the second stage by an orifice plate. For heating, a starvation damper for the first stage chamber is opened, heat is added to the air and its potential energy is reduced to substantially zero by the orifices which the air passes through to the second stage. For cooling, the starvation damper is closed, the first stage runs idle, and intake air for the second stage is drawn directly from the atmosphere to the second stage.

AIR SUPPLY DEVICE FOR AIR HEATING AND COOLING SYSTEM

RELATED APPLICATION

Ser. No. 79,930 filed Oct. 12, 1970, now Pat. Ser. No. 3,698,831 granted Oct. 17, 1972, of which this is a division.

PRIOR ART

OBJECTS

The object of this invention is to improve the efficiency of the heating phase of a combined air heating and cooling unit, for example, of the type mounted on a truck chassis and used for heating or cooling the interior of aircraft. Until recently, these mechanisms were usually provided with heaters of various types which not only were expensive, but which also failed to utilize the heat energy available from the engine which drives the blower for the air which was forced into the aircraft. Now, however, it is intended to provide an extremely simple mechanism, easily shiftable between heating and cooling modes, and closely approaching 100 percent efficiency when operated in the heating mode. To this end there is provided a two-stage blower operable in either of two modes for supplying either heated or substantially unheated air, and shiftable between the two modes simply by controlling a damper for the air intake for the first stage.

Other objects will be apparent from the following specification and drawing, in which the sole Figure is 35 a diagram of the essential parts of the system.

Referring now to the drawing, an air supply duct 2 is provided for feeding hot or cold air to a space, such as the interior of an aircraft. The supply air passes through a heat exchanger 4 which is the evaporator of a refrigerant system, and another heat exchanger 6, which functions as a radiator for the coolant of an internal combustion engine. One or the other of heat exchangers 4 or 6 is active, depending upon whether the system 40 is to operate in heating or cooling mode. Engine 8 has a drive shaft 10 connectable by a clutch 12 to the pump 14 which feeds refrigerant through a circuit 16 running through a condenser 18 and the evaporator-heat exchanger 4, all being conventional components of an air 45 cooling system, the various valves and controls for which are not shown because they are well known. Obviously, heat exchangers 4 and 6 can be combined into one unit.

Engine 8 also has a fan 20 which forces air through 55 a radiator 22 for the engine coolant. By adjustment of valves 24, 26 the engine coolant may be circulated through radiator 22, or alternatively, via circuit 28 through heat exchanger 6. Mechanical power is derived from engine 8 by means of a belt 30 running over a pulley 32 on the engine drive shaft 10 and a pulley 34 on the drive shaft 36 of a two stage blower 38, with which the invention is concerned.

Blower 38 comprises a casing 40 having two working chamber 42 and 44 separated by an orifice plate 46 having a series of orifices 48 near its outer edges. A baffle 50 in working chamber defines between it and orifice plate 46 an intake plenum 52 for working chamber

44. The wall of casing 40 has open ports 54 leading from the atmosphere to intake plenum 52. Working chamber 42 has an intake port 56 regulated by a starvation damper 58, and centrifugal blowers 60, 62 affixed on drive shaft operate in the working chambers. Suitable bearings 64 rotatably support drive shaft 36 in casing 40.

When the system is operated in heating mode, the refrigerating circuit is disabled, valves 24, 26 are adjusted so as to circulate engine coolant through heat exchanger 6, and starvation damper 58 is opened. Air drawn in through intake port 56 is compressed, i.e., work is imparted to the air mass, and the act of compression adiabatically raises the temperature of the air mass. The temperature rise is roughly equal to the BTU value of the horsepower of the work. This work is negated by forcing the air through the orifices, and the potential energy which was added to the air mass in the first stage is reduced to near zero. The air supplied by 15 the first stage is sufficient to meet the demands of the second stage and, ideally, the pressure within the intake plenum 52 is atmospheric pressure, or nearly so, so that little if any air moves through ports 54.

For operating in the cooling mode, the refrigerating system is activated, valves 24, 26 adjusted so as to feed the engine coolant through radiator 22 rather than heat exchanger 6, and starvation damper 58 is closed. Since blower 62 is then imparting very little work to the air trapped within chamber 42, only a small amount of heat is generated. This heat, which enters the second stage by conduction, represents only about ten percent of the heat generated when the starvation damper is open constitutes an acceptable penalty in view of the over-all efficiency and simplicity of the system. In this mode atmospheric air is drawn through ports 54 as indicated by the arrows on leans lines 54.

I claim:

1. An air supply device, comprising a casing divided into first and second working chambers by an orifice plate, said first chamber having an inlet leading to the atmosphere, said second chamber having port means leading to the atmosphere and an air delivery outlet, first and second air impeller respectively operating in said first and second working chambers, means for driving said impellers, damper means for opening and closing the inlet for the first chamber, means forming an air conduit leading from the outlet of said second chamber, an internal combustion engine having a coolant fluid circulation system, a first heat exchanger disposed in said conduit, means for operatively connecting said coolant circulating system to circulate engine coolant through said first heat exchanger, an air cooling system including a pump, a condenser, and a second heat exchanger disposed in said conduit, means for selectively connecting or disconnecting said pump to or from said engine, and means drivingly connecting said engine to said impellers.

2. An air supply device comprising a casing having an interior defined by side walls and opposite end walls, an orifice plate extending from side wall to side wall and disposed between the end walls and dividing

the casing interior into first and second chambers, first and second impellers rotatably mounted in said first and second chambers, respectively, means for driving said impellers, said second chamber having an air delivery outlet disposed for receiving air from the second impeller and having port means for introducing air from the atmosphere to the second impeller, said first chamber having an air inlet for introducing air from the atmosphere to the first impeller, a damper for regulating said air inlet, means forming an air conduit leading from the outlet of said second chamber, an internal combustion engine having a coolant fluid circulating system including a radiator, a first heat exchanger disposed in said conduit, means for selectively connecting said coolant circulatory system to circulate engine coolant through said radiator or said first heat exchanger, an air cooling system including a pump, a condenser, and a second heat exchanger disposed in said conduit, means for selectively drivingly connecting or disconnecting said pump to or from said engine, and

means for drivingly connecting said engine to said impellers.

3. A device for supplying either heater or unheated air to an air duct, comprising a casing divided into first and second working chambers by an orifice plate, said first chamber having an inlet leading to the atmosphere, said second chamber having port means leading to the atmosphere and an air delivery outlet, first and second air impeller respectively operating in said first and second working chambers, means for driving said impellers, damper means for selectively opening and closing the inlet for the first chamber, orifice means through said orifice plate providing a reduction to near zero in the potential energy added by the first impeller to air drawn into the first working chamber when the damper is open, air heating means in said duct, and means for selectively rendering said heating means operable or inoperable to impart heat to the air supplied by said device.
